(57) **CLAIM**

We claim the ornamental design for a smart camera, substantially as shown and described.

DESCRIPTION

FIG. 1 is a front, top, and left-side perspective view of a smart camera showing the new design;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof;

FIG. 8 is a front, bottom, and right-side perspective view of the smart camera shown unfolded;

FIG. 9 is a front view thereof;

FIG. 10 is a back view thereof;

FIG. 11 is a right-side view thereof;

FIG. 12 is a left-side view thereof;

FIG. 13 is a top view thereof;

FIG. 14 is a bottom view thereof;

FIG. 15 is a front, top, and right-side perspective view of the smart camera shown in use;

FIG. 16 is a front, top, and right-side perspective view of the smart camera shown in another state of use; and,

FIG. 17 is a front, top, and right-side perspective view of a smart camera shown folded and in another state of use.

The shaded surfaces visible in FIGS. 1-17 is for the purpose of illustrating claimed surface areas and their boundaries, and form a part of the claimed design. The broken lines showing of a handle and a support in FIGS. 15-17 is for the purpose of illustrating environmental structure and forms no part of the claimed design. All other broken lines in the drawings depict portions of the smart camera that form no part of the claimed design.

1 Claim, 8 Drawing Sheets
